BEST AVAILABLE COPY

FIG. 1 is a perspective view of a swivel chair, embodying my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a cross sectional view on an enlarged scale taken approximately along the line 6—6 of FIG. 4 and looking in the direction of the arrows and wherein the base member of the chair has been omitted for convenience of illustration; and

FIG. 7 is a detailed cross sectional view on an enlarged scale taken approximately along line 7—7 of FIG. 3 and looking in the direction of the arrows.

This application is a continuation-in-part of my earlier filed application Serial No. D. 74,749, filed May 6, 1963 and now abandoned.

I claim:

The ornamental design for a swivel chair, as shown and described.
